UNITED STATES PATENT OFFICE.

WILLIAM D. LOWRY, OF ST. LOUIS, MISSOURI.

UNDERFRAME FOR CARS AND TENDERS.

No. 922,769.

Specification of Letters Patent.

Patented May 25, 1909.

Application filed June 13, 1908. Serial No. 438,272.

To all whom it may concern:

Be it known that I, WILLIAM D. LOWRY, a citizen of the United States, residing at St. Louis, in the county of St. Louis City and State of Missouri, have invented new and useful Improvements in Underframes for Cars and Tenders, of which the following is a specification.

This invention relates to cast steel underframes for freight cars of all descriptions and engine tenders and its object is to provide a strong and substantial underframe adapted to carry a heavy load and consisting of comparatively few parts adapted to be readily assembled and secured together in a simple and expeditious manner.

The invention comprises certain novel improvements on the invention set forth in my application Serial No. 435,854 filed June 20, 1908 and these improvements comprise a sectional center sill with means for connecting the sections thereof in a strong and rigid manner.

In the accompanying drawings Figure 1 is a top plan view of an underframe embodying the invention. Fig. 2 is a longitudinal sectional view through the center sill on the line 2—2 of Fig. 1. Fig. 3 is an enlarged top plan view of a portion of the center sill. Fig. 4 is a transverse sectional view on the line 4—4 of Fig. 1 and showing the body bolster. Fig. 5 is a similar view on the line 5—5 of Fig. 1 and showing a cross tie. Fig. 6 is a detail top plan view of the middle portion of a body bolster. Fig. 7 is a similar view of a cross tie. Fig. 8 is a transverse sectional view of the center sill on the line 8—8 of Figs. 1 and 2. Fig. 9 is a plan view showing the invention embodied in another form. Fig. 10 is a detail sectional view on line 10—10 of Fig. 9 showing the center sill sections connected at the bolster. Fig. 11 is a plan view of Fig. 10.

In the construction illustrated in Fig. 1 the underframe comprises a sectional center sill having two end sections 9, 9', and a middle section 10. The center sill may be U-shape or inverted U-shape in cross section, or it may be made rectangular in cross section throughout its length, but if it is made

U-shape or inverted U-shape the adjacent ends of the sections are preferably made rectangular or box shape. Thus I have shown a center sill of inverted U-shape in cross section (Fig. 8) and at the adjacent ends of the three sections, a cross web or bar 11 is provided at the bottom of each section which makes the adjacent ends of the sections rectangular or box shape (Fig. 2). The end sections of the center sill are connected to the middle section at the cross ties 12, the adjacent ends of the center sill sections meeting at the middle of the cross ties, as clearly shown in Figs. 1, 2. Each cross tie (Fig. 5) is provided with a central recess 13 to receive the center sill and also with two or more integral studs 14 which project up through bosses 11' in the cross webs or bars 11. The center sill sections are provided with outwardly projecting lugs 15 at the top which rest in depressions 15' in the top of the cross ties. A cover plate 16 is seated on the adjacent ends of the center sill sections, in depressions 16' therein (Fig. 2) and on the lugs 15, in the depressions 15' (Fig. 5) so that said plate will lie flush with the top of the center sill and the cross tie. Rivets or bolts 17 pass through the cover plate, lugs 15 and top web 12' of the cross tie to fasten said parts together, and rivets or bolts 17' also fasten the cross tie to the sides of the center sill (Fig. 5). The body bolsters 18 are each provided with a recess 18', like the cross ties, to receive the center sill (Fig. 4) and the latter has a cross web 18'' at its bottom which makes the center sill rectangular or box shape at the bolsters. A stud 19 is made integral with the bolster and it projects upward through an opening 19' in the web 18'' of the center sill. The center sill is provided with lateral lugs 20 which fit in depressions 21 in the top of the bolsters and rivets or bolts 22 pass through these lugs 20 and the top 18'' of the bolsters to fasten the bolsters and the center sill together. Instead of providing two studs 14 and one stud 19 I may use as many studs as may be found desirable. The center sill sections are provided with lateral flanges 23 at the bottom except where the center sill engages the 100

cross ties and the bolsters. The end sills 24 may be made in any suitable manner, separate from the other parts of the underframe, as shown, or cast integral with the end sections 5 of the center sill. The side sills 25 may be made of channel iron or in any other suitable manner and secured to the ends of the cross ties, bolsters and end sills. The stringers 26 may be supported in any suitable manner on the underframe. The bolsters are provided with integral center bearings 27 and side bearings 28.

Instead of making the center sill in three sections connected at the cross ties, as hereinbefore described, I may make it in any other number of sections and in Fig. 9 I have shown a construction in which there is but one cross tie 29 and the center sill 30 is made in four sections connected at the cross tie and 20 at the bolsters 31. In this embodiment of the invention the bolsters will each be provided with two studs 32 (Fig. 10) and the center sill sections will be connected at the bolsters in all substantial respects in the 25 same manner as they are connected at the cross ties as shown in Fig. 2, and the center plate 33 (Fig. 11) also fastened in place in like manner.

My invention provides a strong and substantial underframe which can be easily made and put together. The center sill sections, the cross ties and the bolsters may all be made of cast steel and the end sills and side sills may also be made of cast steel if 35 desired. The studs on the bolsters and cross ties strengthen the connection between these parts and the center sill and add to the strength and rigidity of the underframe, and the studs on the cross ties strengthen the 40 connection between the sections of the center sill. Diagonal braces 34 and cross braces 35 may be used wherever they are found desirable. The end sections of the center sill may be cast integral with the end sills or with the 45 bolsters but it is not considered necessary to illustrate such modifications.

What I claim and desire to secure by Letters Patent is:

1. A cast steel bolster for a car or tender 50 underframe, having a recess to receive the center sill and one or more studs in said recess to engage the center sill.

2. A cast steel bolster for a car or tender 55 underframe provided centrally with a recess opening at the top thereof to receive the center sill, and one or more studs located at the bottom of said recess and integral with the bolster to engage the center sill.

3. A cast steel cross tie for a car or tender 60 underframe, having a recess to receive the center sill and one or more studs in said recess to engage the center sill.

4. A cast steel cross tie for a car or tender 65 underframe provided centrally with a recess opening at the top thereof to receive the cen-

ter sill, and one or more studs located at the bottom of said recess and integral with the cross tie to engage the center sill.

5. In an underframe for cars and tenders, a cast steel center sill made in sections, a transverse member having a recess to receive the ends of two sections of the center sill, and a plurality of integral studs on said member within said recess to engage the ends of the center sill sections. 75

6. In an underframe for cars and tenders, a cast steel center sill made in inverted U-shape in cross sections, a transverse member having a recess to receive the center sill, a web forming a bottom for the center sill at 80 the transverse member, and one or more studs integral with said member to engage said web.

7. In an underframe for cars and tenders, a cast steel center sill made in sections, a transverse member having a recess to receive the ends of two sections of the center sill, a web on said ends forming a bottom for the center sill at the transverse member, and a plurality of studs on the transverse member 90 to engage the web at the ends of the center sill sections.

8. In an underframe for cars and tenders, a cast steel center sill made in sections, a cast steel cross tie having a recess to receive the 95 ends of two sections of the center sill, and integral studs on the cross tie to engage said ends of the center sill sections.

9. In an underframe for cars and tenders, a cast steel center sill made in sections arranged end to end, said sections being provided at their adjacent ends with openings, transverse members each provided centrally with a recess to receive the ends of two center sill sections, and integral studs on the transverse members in said recesses to engage the 105 openings in the center sill sections.

10. In an underframe for cars and tenders, a cast steel center sill made in sections arranged end to end, a cross tie provided centrally with a recess to receive the center sill and located at the adjacent ends of two sections thereof, studs on the cross tie extending up through the bottom of the center sill, lugs on the center sill overlapping the cross tie, 115 and bolts or rivets fastening the lugs to the cross tie.

11. In an underframe for cars and tenders, a cast steel center sill made in sections, a transverse member having a recess to receive the 120 ends of two sections of the center sill, a plurality of integral studs on said member within said recess to engage the ends of the center sill sections, the ends of the center sill sections and the adjacent parts of the transverse member being depressed at the top, and a cover plate seated in said depression and fastened to the sill sections and transverse member. 125

12. In an underframe for cars and tenders, 130

a cast steel center sill made in sections arranged end to end, cross ties provided centrally with recesses to receive said center sill and located at the adjacent ends of said sections, studs on said cross ties extending up through the bottom of the center sill sections, bolsters provided centrally with recesses to

receive said center sill, and studs on said bolsters engaging said center sill.
